(57) CLAIM

The ornamental design for a reel as shown and described.

DESCRIPTION

FIG. 1 is a perspective view of a reel;

FIG. 2 is a top plan view of the reel;

FIG. 3 is a front elevation view of the reel;

FIG. 4 is a left side elevation view of the reel;

FIG. 5 is a rear elevation view of reel;

FIG. 6 is a right side elevation view of the reel; and,

FIG. 7 is a bottom plan view of the reel.

Broken lines shown in the drawing views are included for illustrative purposes only and form no part of the claimed design.

1 Claim, 5 Drawing Sheets

FIG. 1

FIG. 2FIG. 3*FIG. 4*FIG. 5*FIG. 6FIG. 7
